[57] CLAIM

The ornamental design for a motor vehicle body, as shown and described.

DESCRIPTION

FIG. 1 is a front perspective view of a motor vehicle body showing our new design with the side doors in open condition;

FIG. 2 is a rear perspective view thereof with the side doors in closed condition;

FIG. 3 is a perspective view of the front and right side thereof with the side doors in closed condition;

FIG. 4 is a perspective view of the rear with left side thereof with the side doors in closed condition;

FIG. 5 is a left side elevational view thereof with the side doors in closed condition;

FIG. 6 is a top plan view thereof with the side doors in closed condition; and,

FIG. 7 is a top plan view thereof with the side doors in open condition.

The broken line showing of environmental structure in FIGS. 1, 2, 3, 5 and 7 of the drawing is for illustrative purposes only and forms no part of the claimed design.
